UNITED STATES PATENT OFFICE.

JOSEPH A. CRISMORE, OF CHICAGO, ILLINOIS.

WOOD-CUTTING MACHINE.

SPECIFICATION forming part of Letters Patent No. 705,324, dated July 22, 1902.

Application filed March 7, 1902. Serial No. 97,127. (No model.)

To all whom it may concern:

Be it known that I, JOSEPH A. CRISMORE, a citizen of the United States, residing at Chicago, county of Cook, State of Illinois, have 5 invented a certain new and useful Improvement in Wood-Cutting Machines; and I declare the following to be a full, clear, and exact description of the invention, such as will enable others skilled in the art to which it 10 pertains to make and use the same, reference being had to the accompanying drawings, which form a part of this specification.

My invention relates in general to machines for beveling strips of wood to form miter-joints, and more particularly to machines for cutting the ends of strips of moldings so as to form simultaneously the miter-bevel and the grooves to conform to the contour of the surface of the molding.

20 In carpentry it is customary in forming joints between moldings to cut in the end of one strip projections and grooves to engage the raised portions and grooves on the surface of the other strip of the joint. It has 25 heretofore been usual to cut the desired bevel on the end of the strip in one operation and to cut what is technically known as the "coping"—that is, the grooves to receive the raised portions of the surface of the other 30 strip of the joint—by a separate operation.

The object of my invention is to produce a machine for cutting strips of molding so as to form simultaneously the miter-bevel and coping.

35 A further object of my invention is to provide a machine of the character above referred to which will be simple in construction, inexpensive in manufacture, and efficient in operation.

40 My invention, briefly described, consists in a horizontally-reciprocating blade the cross-section of the cutting edge of which conforms to the raised and reentrant portions of the surface of the molding, the desired miter-bevel being produced by adjusting the angular position of the molding with respect to the plane of movement of the blade.

45 My invention will be more fully described hereinafter with reference to the accompanying drawings, in which the same is illustrated in a convenient and practical form, and in which—

Figure 1 is an elevational view of my invention; Fig. 2, a cross-sectional view taken on line 2 2, Fig. 1, looking in the direction of the arrows; Fig. 3, a sectional plan view on a plane below the top bar A³; and Fig. 4, a perspective detached view of one of the supports, a portion thereof being broken away.

The same reference characters are used to 60 designate the same parts in all the figures of the drawings.

Reference-letter A indicates a base, preferably composed of cast metal and comprising a horizontal portion and a vertical portion. The vertical portion consists in ends A' and A², connected by a top A³. The arrangement of the ends and top with respect to the horizontal portion of the base is such as to form an opening in which the cutting-blade is adapted to reciprocate. Grooves a³ are formed in the under surface of the top portion A³ and in the upper surface of the base immediately below the top portion. Within these grooves is guided a support C, 75 to which is secured the cutting-blade. The end edges of the support C are preferably inclined downwardly, so as to converge at their bottoms, as shown in Fig. 1. The support C is provided with a horizontally-projecting flange c, in the under surface of which are formed gear-teeth c'. The horizontal portion of the base immediately below the flange c is provided with gear-teeth a. A gear-wheel G is located between the base A and the flange c and is provided with gear-teeth which mesh 85 with the teeth c' and a. The gear-wheel G is provided with a laterally-projecting portion g', in which a socket is formed to receive the lower end of a lever G'.

90 The cutting-blade D is secured to the support C preferably by bolts and slots d d, as clearly indicated in Fig. 1. The cutting edge of the blade D is of a cross-section to produce in the molding which it engages grooves and 95 projections corresponding to the raised and depressed portions in the surface of the molding with which the end portion which is cut by the blade is to engage. In the drawings I have shown the blade as consisting in a straight edge d', an offset cutting portion d², below which is a straight cutting portion d³ in the same vertical plane as the cutting portion d', and a second offset cutting portion

*d*⁴, below which is a third straight edge *d*⁵ in the same vertical plane as the edges *d*' and *d*³. The blade *D* is preferably provided with cutting edges at each side thereof, as illustrated in Fig. 1.

The end portions *A'* and *A*² of the base of the machine are provided with grooves *a*² and *a*⁴, located in the path of movement of the offset portions *d*² and *d*⁴ of the cutting-blade. The surfaces of the end portions *A'* and *A*² above and below and between the grooves *a*² and *a*⁴ are in the same vertical plane and are so located as to permit the portions *d*', *d*³, and *d*⁵ of the cutting-blade to pass in front thereof. In order that the strips of molding or other material which is to be cut in the machine may be retained in the path of reciprocation of the blade, adjustable supports *B'* and *B*² are provided. These supports are pivoted adjacent to the end portions *A'* and *A*² of the base, so as to swing from a position at right angles to the plane of the knife toward a plane parallel and adjacent to the blade. These supports may be retained in any desired angular position with respect to the path of the blade by means of screw-clamps *e'* engaging grooves *f'*, formed through the horizontal portion of the base. The supports *B'* and *B*² may be adjusted so as to vary the angular position of the material which is to be cut with relation to the plane of reciprocation of the cutting-blade, thereby determining the degree of bevel of the miter cut.

The cutting-blade may be of a cross-section to conform to the surface of a single strip of molding of predetermined design, or the blade may be provided with cutting portions each of which is adapted to produce a cut edge conforming to a given molding, thereby rendering the machine capable of cutting edges of different design. The cutting-blade illustrated in the drawings is adapted to cut the ends of two different moldings, accordingly as the strip to be cut is supported in the plane of the lower half of the cutting-blade or in the plane of the upper half of the cutting-blade. The offset portion *d*², for instance, may be designed to cut a coping of one and one-half inches, while the offset portion *d*⁴ may be designed to cut a coping of one and three-fourths inches.

In order that the material which is to be cut may be supported in position to be engaged by either the lower or upper halves of the cutting-blade, the adjustable supports *B'* and *B*² are provided with seats *b'* and *b*², the former of which supports the strip of molding in position to be engaged by the upper part of the knife, while the latter, *b*², retains the molding in position to be engaged by the lower portion of the cutting-blade.

The operation of my invention is as follows: One of the supports *B'* or *B*² is adjusted to the desired angular position with respect to the cutting-blade and there secured by means of the clamp-screw *e'* engaging the groove *f'*. If the left cutting edge of the blade is to be

used, the support *B'* is adjusted to the desired position, while if the opposite edge of the blade is to do the cutting the other adjustable support *B*² is secured in the desired angular position. The end of the strip which is to be cut is then inserted in front of the cutting-blade and held against the adjustable support. The lever *G'* is then oscillated, which partially rotates the gear *G*. As the teeth *g* of the gear engage the fixed rack *a* the teeth at the upper periphery move in the direction in which the lever is forced, thereby through the engagement of the teeth on the gear-wheel with the rack-bar *c'* on the support *C* sliding the latter in the guide-grooves *a*³ *a*³ and causing the cutting edge of the blade, which is rigidly secured to the support *C*, to remove that portion of the strip of molding which projects beyond the path of movement of the blade. The lever *G'* may then be moved in a reversed direction, thereby rolling the gear through the engagement of its teeth with the fixed rack, which reciprocates the knife to its initial position through the engagement of the teeth on the gear-wheel with the rack-bar *c'* on the blade-support *C*. When the cutting-blade is adapted to cut two or more different copings, if the lower portion of the blade is to be used the strip of molding is placed directly upon the horizontal portion of the base and rests against the lateral projecting portion *b*² of the adjustable support *B*². If, however, the upper portion of the cutting-blade is to be utilized, the strip of molding is seated upon the projection *b'*, whereby it is retained in the plane of movement of the upper portion of the blade.

From the foregoing description it will be observed that I have produced a machine for simultaneously cutting a miter and a coping of predetermined design, thereby producing at a single operation that which has ordinarily heretofore been effected by two separate operations. It will also be observed that a miter and two copings of different design may be cut upon a single machine by varying the vertical position of the material which is to be cut in the path of the cutting-blade.

While I have described more or less precisely the details of construction, I do not wish to be understood as limiting myself thereto, as I contemplate changes in form, the proportion of parts, and the substitution of equivalents, as circumstances may suggest or render expedient, without departing from the spirit of my invention.

Having now fully described my invention, what I claim as new, and desire to secure by Letters Patent, is—

1. In a machine for simultaneously forming miter and coping cuts, the combination with a cutting-blade conforming to the contour of the surface of a molding, of a base upon which the blade is guided having a vertical face adjacent to the path of movement of the blade corresponding to the cutting-surface of the blade, means for reciprocating said blade,

and means for supporting the molding in the path of the blade.

2. In a machine for simultaneously forming miter and coping cuts, the combination with a horizontally-reciprocating cutting-blade having cutting edges at each end thereof conforming to the contour of the surface of a molding, of a support to which the blade is rigidly secured, a base upon which said support is guided, means for reciprocating said support, and adjustable means for supporting the molding in the path of the blade.

3. In a machine for simultaneously forming miter and coping cuts, an integral cutting-blade comprising vertically-aligned portions conforming to the contour of the surfaces of a plurality of moldings.

4. In a machine for simultaneously forming miter and coping cuts, the combination with a cutting-blade comprising vertically-aligned portions conforming to the contour of the surfaces of a plurality of moldings, of a support to which said blade is rigidly secured, means for horizontally reciprocating said support, and means for supporting the molding in the path of the blade.

5. In a machine for simultaneously forming miter and coping cuts, the combination with a cutting-blade comprising portions conforming to the contour of the surfaces of a plurality of moldings, of a support to which said blade is rigidly secured, means for horizontally reciprocating said support, and

means for supporting a molding in different horizontal planes in the path of the blade.

6. In a machine for simultaneously forming miter and coping cuts, the combination with a cutting-blade comprising portions conforming to the contour of the surfaces of a plurality of moldings, of a base upon which the blade is guided having a vertical face adjacent to the path of movement of the blade corresponding to the cutting-surface of the blade, means for reciprocating said blade, and means for supporting a molding in the path of movement of the blade.

7. In a machine for simultaneously forming miter and coping cuts, the combination with a cutting-blade comprising portions conforming to the contour of the surfaces of a plurality of moldings, of a base upon which the blade is guided having a vertical face adjacent to the path of movement of the blade corresponding to the cutting-surface of the blade, means for reciprocating said blade, a pivoted support swinging about a vertical axis adjacent to the plane of movement of the blade, and a plurality of seats carried by said support in different horizontal planes to receive a molding and locate the same in the desired vertical relation to the blade.

In testimony whereof I sign this specification in the presence of two witnesses.

JOSEPH A. CRISMORE.
